Joseph Bloom

UNITED STATES PATENT OFFICE.

JOS. BLOOM, OF PHILADELPHIA, PENNSYLVANIA, ASSIGNOR TO R. E. ROGERS, OF SAME PLACE.

UMBRELLA-FRAME.

Specification of Letters Patent No. 22,686, dated January 18, 1859.

To all whom it may concern:

Be it known that I, JOSEPH BLOOM, of the city of Philadelphia, in the State of Pennsylvania, have invented certain new and useful Improvements in the Construction of Umbrella and Parasol Frames; and I do hereby declare that the following is a full and exact description thereof, reference being had to the accompanying drawings and to the letters and marks thereon.

My invention relates, first, to the construction of the bow or rib and brace of the frame; second, to means for connecting the bow or rib and brace to the stem or standard; and, third, to means for connecting the brace to the bow or rib.

To enable others skilled in the art to make and use my invention, I will proceed to describe its construction and operation.

By Figure 1 of the drawings is represented the handle, stem or standard of an umbrella, with a bow or rib, a brace or sustaining rod, and the means for connecting these parts to each other. By Fig. 2, is shown, a part of the stem or standard with collars, screw threads and nuts for securing the ends of the bows and braces to the standard, and the ends of a bow and brace fitted into the collar and nut. Fig. 3, shows a section of a bow or rib with the spring-clasp for connecting the brace to the rib. Fig. 4, an inner end piece of a rib; and Fig. 5, a transverse sectional view of a rib or bow or brace.

In each of these figures like letters designate like parts.

(a) indicates the handle, (b) the stem or standard, (c) the bow or rib, (d) the brace or sustaining rod, (e) the spring-clasp, (f, f) collars upon the stem or standard, (g, g) the clamping nuts of the collars and (h) the catch or latch for holding the brace when the umbrella is opened or closed. The bow or rib and brace, as is seen by these figures, are so constructed as to have the upper side curved or arched with a lip or feather upon the inner or under side. This form of the rib and brace is more fully shown by Fig. 5, (i) indicating the lip or feather. These ribs and braces can be made of steel or other suitable material, very light and yet strong. The curved upper side of the bow or rib gives a broad surface for the bearing of the silk, or fabric of which the covering is made, while the lip or thread greatly

adds to the strength. Both bows or ribs and brace may be of one piece of metal by being drawn through dies with the proper faces or recesses for giving the form, or they may be made of two pieces the one being a rolled plate or strip to which the wire for the other may be soldered.

The inner end of the bows or ribs and both ends of the braces, as will be seen by referring to Fig. 4, have a piece removed from either side near the end, by which a stud or process is left projecting on each side, marked (b) in the figure alluded to. This stud or process fits into recesses in the collars and nuts shown fully in Fig. 2. The turning of the nut so as to unscrew it allows of the removal of any one or more of the ribs or braces, so that in case of fracture or any injury making it necessary to remove a bow or brace, it can readily be replaced and the repair made in a moment.

The outer end of the brace is connected to the bow or rib by the intervention of a spring-clasp (e), the studs or processes of the brace fitting into holes in the ears or lugs of the clasp, the clasp being so far yielding as to permit the lugs or ears to be forced apart for the introduction or removal of the ends of the braces. The clasp itself may be readily removed. Fig. 3 shows a depression on the upper side of the bow at the point where the clasp or band is attached to it, and a thickening or enlargement at the same point on the underside. By this depression or recess and thickening of the bow the clasp or band has formed for it a holding surface, while the bow is strengthened at a point where it is subjected to strain.

These improvements render the frame of an umbrella or parasol one of easy and ready repair; as when the slight attachments of the silk or covering are broken, any one or more of the braces or bows can be taken out and replaced by simply unscrewing the nuts and springing open the clasp or band from its recess on the bow or rib. Every part of the frame is detachable.

Having thus fully set out my invention, what I claim as new in the construction of umbrella and parasol frames and desire to secure by Letters Patent is—

1. The bow or rib constructed substantially as described.

I am aware that the bow or rib and the

brace or sustaining rod have been attached to collars upon the standard by a piece of metal having an enlarged end affixed to the end of the bow or rib, and a like piece of metal affixed to the end of the brace, the enlarged end fitting into a slit of a sheet metal collar the flange of which must be swaged down upon the enlarged end in order to hold it in place, and I, therefore, do not claim this method, but I do claim—

2. Connecting the bow or rib and the brace or sustaining rod to the collars upon the stem or standard by the means herein set forth.

3. I am, also, aware that the end of the brace or sustaining rod has been connected

to the bow or rib by the end of the brace being riveted to a band which may be sprung into a groove in the inner surface of the bow or rib and I, therefore, do not claim this method of connecting the two parts here named, but what I do claim is—

3. Connecting the brace or sustaining rod to the bow or rib by the spring-band embracing the bow as herein set forth. 25

Signed at Philadelphia this 19th day of October 1858.

J. BLOOM.
